UNITED STATES PATENT OFFICE.

HERMAN RICHMAN, OF MARINERS HARBOR, NEW YORK, ASSIGNOR TO L. STRAUS & SONS, A COPARTNERSHIP CONSISTING OF NATHAN STRAUS AND LEE KOHNS, OF NEW YORK, N. Y.

DESIGN FOR A CUT-GLASS PLATE OR SIMILAR ARTICLE.

51,080.

Specification for Design.

Patented July 24, 1917.

Application filed February 27, 1917. Serial No. 151,352. Term of patent 7 years.

To all whom it may concern:

Be it known that I, HERMAN RICHMAN, a citizen of the United States, residing at Mariners Harbor, in the county of Richmond and State of New York, have invented a new, original, and ornamental Design for Cut-Glass Plates or Similar Articles, of which the following is a specification, reference being had to the accompanying drawing, wherein—

The figure is a bottom view of the plate illustrating my new design.

I claim:

The ornamental design for a cut glass plate or similar article, as shown.

HERMAN RICHMAN. [L.S.]
